UNITED STATES PATENT OFFICE

2,601,135

FIREARM WITH TIME DELAY FIRING
MEANSGustaf W. Hammar, Rochester, N. Y., assignor to
the United States of America as represented
by the Secretary of War

Application November 8, 1948, Serial No. 58,921

4 Claims. (Cl. 42—1)

1

This invention relates to a firearm, more particularly to a firearm for use in delayed firing for simulating the fire of rifles or machine guns.

For tactical reasons it is sometimes desirable to mislead the enemy into believing that large forces of men are concentrated in various areas in order that a surprise attack may be instituted at a different point. Such a diversion has been accomplished by a few men firing a large number of firearms as rapidly as possible and then upon completion of the diversion, such men have attempted to withdraw to a more secure position. Unfortunately in a maneuver of this type considerable quantities of firearms have to be abandoned and the loss of men may be quite high.

Obviously to overcome such loss in men and equipment a firing device which can be mounted prior to such a diversionary maneuver and which can be set to fire at a predetermined time will be required. Such a device will of course be expendable and consequently must be exceedingly cheap to produce and likewise be light and easily attached to a tree or other support.

Accordingly it is an object of this invention to provide a firearm for use in simulating the fire of firearms operated by troops.

Another object of this invention is to provide a firing device arranged to be fired by a time delay element whereby such firing device may be set to go off after a selected time interval as governed by such delay element.

Another object of this invention is to provide a firing device for simulating the fire of troops which can be conveniently secured to any suitable support at hand.

The specific nature of the invention as well as other objects and advantages thereof will clearly appear from a description of a preferred embodiment as shown in the accompanying drawings in which:

Fig. 1 is a side view of the firing device.

Fig. 2 is a left end view of the device shown in Fig. 1.

Fig. 3 is a longitudinal sectional view taken along the line 3—3 of Fig. 2.

Fig. 4 is a cross-sectional view taken along the line 4—4 of Fig. 3.

Fig. 5 is a top view of Fig. 1.

Fig. 6 is a side view of an alternate form of the invention.

Fig. 7 is a longitudinal sectional view of the device shown in Fig. 6.

In Figs. 1 and 3 there is shown in assembled relation the firing device of this invention. Such device comprises mainly a barrel 10, a breech plug

2

11 and a barrel supporting member 12. Barrel 10 is provided with an axial bore 13 shown in Fig. 3 and a chamber 14 in the breech end thereof to accommodate a cartridge 15 insertable therein. The cartridge preferably utilized with this device is known as the U. S. carbine cal. .30 M1 cartridge. It will be appreciated however that this device can be readily proportioned to utilize any ammunition. The breech end of barrel 10 is counterbored and threaded as shown at 16 in which is screwed the breech plug 11.

Breech plug 11 is provided with an exteriorly threaded end 17 which cooperates with threaded counterbore 16 whereby such breech plug is secured to barrel 10. The other end of breech plug 11 is of greatly reduced diameter as shown at 18. An axial hole 19 is provided in plug 11 and the reduced diameter end 18 is provided with a counterbore 20 coaxial with hole 19. A headed firing pin 21 is inserted in hole 19 and the head of such pin is engageable with the bottom of counterbore 20 when the firing pin projects out of hole 19. An annular groove 22 is provided about the periphery of reduced diameter end 18 on breech plug 11 for a purpose to be later described.

Barrel supporting member 12 is preferably made from sheet steel blanked out and then bent to the form shown in Fig. 1. Such barrel supporting member is provided with a handle portion 23 and such handle portion is of inverted U-shape as shown in Fig. 4. Barrel supporting member 12 partially surrounds barrel 10 and may be secured to such barrel by welding or by screws, as desired. A pair of depending opposed lugs 24 are provided on barrel supporting member 12 near the breech end of barrel 10. Forwardly of lugs 24 on the underside of support member 12 there are provided a plurality of triangularly shaped teeth 25.

40 A movable jaw 26 provided with a handle portion 27 is pivotally secured to lugs 24 by a pin 28. Movable jaw 26 is of the same construction as barrel supporting member 12 and is of generally U-shape cross-section as shown in Fig. 2. Handle portion 27 is disposed at an obtuse angle to the jaw portion whereby the movable jaw 26 may be pivoted away from teeth 25 of barrel supporting member 12. Corresponding teeth 29 are provided on movable jaw 26 which are opposed to teeth 25. A torsion spring 30 surrounds pin 28 and is engageable with jaw 26 in such fashion as to bias the jaw 26 to the closed position shown in Fig. 2.

In Figs. 6 and 7 there is illustrated a firing device 55 vice similar to that shown in Figs. 1 and 3 but of

modified form. The device illustrated in such figures however lies within the scope of this invention and comprises mainly a barrel 31, breech plug 32 similar to breech plug 11 and secured in a corresponding fashion to barrel 31. A firing pin 33 is axially mounted in breech plug 32 in a manner corresponding to that described for the first-mentioned device. Barrel 31 accommodates a cartridge 34 which in this instance is a large caliber revolver cartridge.

A barrel supporting member 35 is secured to an integral depending lug 36 provided on barrel 31 by rivets 37. Barrel supporting member 35 has a forwardly projecting jaw portion 38 provided with a plurality of saw teeth 39. A handle portion 40 is provided on barrel supporting member 35 obliquely disposed to the axis of barrel 31. A movable jaw 41 having an integral handle portion 42 disposed at approximately a right angle to jaw 41 is pivotally mounted to barrel supporting member 35 by a pin 43 transversely disposed through each of such members. Corresponding teeth 44 are provided on movable jaw 41 which are opposed to teeth 39. A spring 44 surrounds pin 43 and a leg 45 of such spring bears against handle 42 while another leg 46 of spring 44 bears against handle 40. Thus spring 44 biases handles 42 and 40 apart thereby tending to close jaws 41 and 38 by means of such handles. Jaws 38 and 41 are readily opened so that the firing device may be conveniently mounted on a suitable support.

A device known as a time pencil 47 is axially mounted on the reduced diameter portion 18 of breech plug 11 of the device shown in Fig. 3. Such time pencil comprises a tube 48 which is placed over reduced diameter portion 18 of plug 11 and crimped into annular groove 22. A striker 49 is slidably mounted within tube 48. Such striker is provided with spaced bearing portions 50 and 51 which slidably engage the inner wall of tube 48. A spring 53 surrounds striker 49 and one end thereof is secured to tube 48 by a rivet 54. The other end of spring 53 is secured to bearing member 51 by a rivet 55. A transverse pin 56 is secured near the right end of time pencil 47 as shown in Fig. 3 and an axially disposed wire 57 is secured to pin 56 by winding a turn or two thereabouts or such spring may be secured in some other fashion. The other end of wire 57 is secured to bearing member 51 preferably by welding. Wire 57 secures striker 49 in a cocked position within tube 48, spring 53 being in tension so that when wire 57 is fractured or parted as will be presently described, spring 53 will bias striker 49 forwardly.

A capsule 58 is cemented or otherwise secured in the end of time pencil 47 as shown in Fig. 3. Such capsule contains an acid which will readily attack the metal of which wire 57 is constructed. Capsule 58 may be of metal, glass, or other readily punctured or fractured material. Some suitable absorbent material, as indicated at 59, surrounds wire 57 in order to absorb the acid flowing out of capsule 58 so that such acid may be brought into intimate contact with wire 57. Time pencil 47 is also utilized with the device shown in Figs. 6 and 7 and further description thereof is not deemed necessary.

Cartridge 15 is readily inserted into chamber 14 of barrel 10 by simply unscrewing breech plug 11 thus providing access to chamber 14. Breech plug 11 is then secured within threaded counter-bore 16 whereupon the device is ready to be fired. Barrel 10 may be mounted on a sapling or other

suitable support by opening movable jaw 26 by simply grasping handles 23 and 27 and forcing such together, whereupon the handle is released so that teeth 25 and 29 will securely grab the sapling or other support.

Cartridge 34 is inserted in barrel 31 of the device shown in Figs. 6 and 7 in a similar manner as that above described and such device may be mounted on a sapling or other suitable support by simply opening jaws 38 and 41 as described above.

The time of firing or discharge of the device is governed entirely by the time pencil so that by proper selection of the time pencil any desired delay in the discharge of the cartridge may be effected within the limits of the time pencil. With the device mounted on a tree or other suitable support, the time pencil is activated by rupturing or breaking capsule 58 whereupon the acid therein will flow forwardly to be absorbed by the absorbent material 59 whereupon the acid will be directed into intimate contact with wire 57 and will thus react with the metal to slowly dissolve such metal. When wire 57 has been weakened to the point where the bias of spring 53 is sufficient to separate wire 57, such spring will bias striker 49 forwardly to strike firing pin 21 a smart blow whereupon discharge of the cartridge 15 is effected. Obviously by varying the diameter of wire 57 greater or shorter periods of delay in firing the cartridge may be conveniently obtained. The device shown in Figs. 6 and 7 with time pencil 47 secured thereto functions in an identical manner.

From the foregoing description it is readily apparent that there is here provided a simple device for simulating the fire of troops with a device which is simple, inexpensive and positive in operation. Great numbers of such devices may be readily mounted in any given area and then set to fire intermittently by breaking the time pencil. A comparatively small number of men can quickly place such devices and then can rapidly and undetected leave the scene. It is further pointed out that the device being relatively inexpensive to manufacture is expendable.

I claim:

1. A firearm comprising a support, a barrel secured to said support, a breech plug removably secured to said barrel, a firing pin in said breech plug, a tube mounted on said plug and communicating with said firing pin, a spring-biased striker mounted in said tube for cooperation with said firing pin movable between a cocked position and a fired position, a severable member within said tube for holding said striker in the cocked position, and means in said tube for severing said member after a predetermined variable time interval thereby releasing said striker from the cocked position.
2. In a firearm having a support and a barrel secured thereto, the combination of, a breech plug removably secured to said barrel, a tube mounted on said plug, firing means mounted in said tube for movement between a cocked position and a fired position, a time pencil within said tube for releasably retaining said firing means in a cocked position, and means in said tube for releasing said firing means from said pencil after a predetermined variable time interval.
3. In a firearm having a support and a barrel secured thereto, the combination of, a breech plug removably secured to said barrel, a firing pin in said breech plug, a tube mounted on said

plug and communicating with said firing pin, a spring-biased striker mounted in said tube for cooperation with said firing pin movable between a cocked position and a fired position, a time pencil within said tube for releasably retaining said striker in the cocked position, and a frangible capsule having an acid eating constituent therein for releasing said pencil from said striker by erosion when said capsule is broken after a predetermined variable time interval.

4. In a firearm having a barrel and a rearwardly extending housing, the combination of, a U-shaped handle partially surrounding the housing and being provided with forwardly extending vertical arms that are fixedly secured to either side of the barrel, each of said arms having a plurality of downwardly depending teeth longitudinally disposed in relation to the axis of the barrel, each of said arms being provided with a depending lug rearwardly of said teeth to receive a transverse pin, and a spring-biased U-

shaped clamp mounted on said pin having a handle portion or the rear end thereof and a plurality of upwardly depending teeth forwardly thereto, whereby said downwardly and said upwardly depending teeth provide means to resiliently mount the firearm to an object.
